US00D924763S

(12) **United States Design Patent** (10) **Patent No.:** **US D924,763 S**
(45) **Date of Patent:** **** Jul. 13, 2021**

(54) **VEHICLE OCCUPANT SUPPORT**

(71) Applicant: **Arjuna Indraeswaran Rajasingham**,
Bethesda, MD (US)

(72) Inventor: **Arjuna Indraeswaran Rajasingham**,
Bethesda, MD (US)

(**) Term: **15 Years**

(21) Appl. No.: **29/739,599**

(22) Filed: **Jun. 26, 2020**

Related U.S. Application Data

(63) Continuation-in-part of application No. 16/855,181, filed on Apr. 22, 2020, now Pat. No. 10,921,885, and a continuation-in-part of application No. 16/884,479, filed on May 27, 2020, and a continuation-in-part of application No. 16/855,181, filed on Apr. 22, 2020, now Pat. No. 10,921,885, and a continuation-in-part of application No. 16/430,061, filed on Jun. 3, 2019, which is a continuation-in-part of application No. PCT/US2017/064626, filed on Dec. 5, 2017, and a continuation-in-part of application No. 14/203,088, filed on Mar. 10, 2014, now Pat. No. 10,423,295, which is a continuation-in-part of application No. 13/694,996, filed on Jan. 24, 2013, said application No. PCT/US2017/064626 is a continuation-in-part of application No. 14/708,584, filed on May 11, 2015, now Pat. No. 10,120,440, said application No. 16/884,479 is a continuation-in-part of application No. 16/430,061, filed on Jun. 3, 2019, which is a continuation-in-part of application No. 14/203,088, filed on Mar. 10, 2014, now Pat. No. 10,423,295, said application No. 16/884,479 is a continuation-in-part of application No. 16/430,061, filed on Jun. 3, 2019, which is a continuation-in-part of application No. 13/694,996, filed on Jan. 24, 2013, said application No. 16/884,479 is a continuation-in-part of application No. 16/430,061, filed on Jun. 3, 2019, which is a continuation-in-part of application No. 16/138,998, filed on Sep. 22, 2018, which is a

continuation-in-part of application No. 15/203,882, filed on Jul. 7, 2016, now Pat. No. 10,703,483, which is a continuation-in-part of application No. 14/375,673, filed as application No. PCT/US2013/000024 on Jul. 30, 2014, now Pat. No. (Continued)

(57) **CLAIM**

The ornamental design for a vehicle occupant support, as shown and described.

DESCRIPTION

FIG. 1 is a Left Elevational view showing a vehicle occupant support;

FIG. 2 is a Top (Plan) View thereof;

FIG. 3 is a Front elevation view thereof;

FIG. 4 is an isometric view 1 thereof;

FIG. 5 is an isometric view 2 thereof; and,

FIG. 6 is an isometric view with the shoulder stop and auxiliary body support deployed of the vehicle occupant support.

1 Claim, 6 Drawing Sheets

Related U.S. Application Data

9,868,416, said application No. 16/884,479 is a continuation-in-part of application No. 16/430,061, filed on Jun. 3, 2019, which is a continuation-in-part of application No. 16/138,998, filed on Sep. 22, 2018, which is a continuation-in-part of application No. 15/872,108, filed on Jan. 16, 2018, which is a continuation-in-part of application No. 15/143,168, filed on Apr. 29, 2016, now Pat. No. 10,556,523, said application No. 16/884,479 is a continuation-in-part of application No. 16/430,061, filed on Jun. 3, 2019, which is a continuation-in-part of application No. 16/138,998, filed on Sep. 22, 2018, which is a continuation-in-part of application No. 15/143,168, filed on Apr. 29, 2016, now Pat. No. 10,556,523, which is a continuation-in-part of application No. 13/820,510, filed as application No. PCT/US2011/001547 on Mar. 2, 2013, now Pat. No. 9,358,908, said application No. 16/884,479 is a continuation-in-part of application No. 16/430,061, filed on Jun. 3, 2019, which is a continuation-in-part of application No. 16/138,998, filed on Sep. 22, 2018, which is a continuation-in-part of application No. 15/143,168, filed on Apr. 29, 2016, now Pat. No. 10,556,523, which is a continuation-in-part of application No. 14/461,395, filed on Aug. 16, 2014, now Pat. No. 9,440,563, which is a continuation-in-part of application No. 12/451,317, filed on Nov. 6, 2009, now Pat. No. 8,864,229, said application No. 16/884,479 is a continuation-in-part of application No. 16/430,061, filed on Jun. 3, 2019, which is a continuation-in-part of application No. 16/138,998, filed on Sep. 22, 2018, which is a continuation-in-part of application No. 15/143,168, filed on Apr. 29, 2016, now Pat. No. 10,556,523, which is a continuation-in-part of application No. 14/210,413, filed on Mar. 13, 2014, now Pat. No. 9,428,088, which is a continuation-in-part of application No. 12/735,146, filed as application No. PCT/US2009/003432 on Jun. 17, 2010, now Pat. No. 8,763,954, said application No. 16/884,479 is a continuation-in-part of application No. 16/430,061, filed on Jun. 3, 2019, which is a continuation-in-part of application No. 16/138,998, filed on Sep. 22, 2018, which is a continuation-in-part of application No. 15/143,168, filed on Apr. 29, 2016, now Pat. No. 10,556,523, which is a continuation-in-part of application No. 14/848,575, filed on Sep. 9, 2015, now Pat. No. 9,669,739, which is a continuation-in-part of application No. 13/138,183, filed on Jul. 18, 2011, now Pat. No. 9,174,555, said application No. 16/884,479 is a continuation-in-part of application No. 16/430,061, filed on Jun. 3, 2019, which is a continuation-in-part of application No. 16/138,998, filed on Sep. 22, 2018, which is a continuation-in-part of application No. 15/203,882, filed on Jul. 7, 2016, now Pat. No. 10,703,483, which is a continuation-in-part of application No. 14/210,413, filed on Mar. 13, 2014, now Pat. No. 9,428,088, which is a continuation-in-part of application No. 12/735,146, filed as application No. PCT/US2009/000342 on Jun. 17, 2010, now Pat. No. 8,763,954, said application No. 16/884,479 is a continuation-in-part of application No. 16/430,061, filed on Jun. 3, 2019, which is a continuation-in-part of application No. 16/138,998, filed on Sep. 22, 2018, which is a continuation-in-part of application No. 15/872,108, filed on Jan. 16, 2018,

which is a continuation-in-part of application No. 14/903,573, filed as application No. PCT/US2014/045727 on Jan. 7, 2016, now Pat. No. 10,173,779, said application No. 16/884,479 is a continuation-in-part of application No. 16/430,061, filed on Jun. 3, 2019, which is a continuation-in-part of application No. 16/138,998, filed on Sep. 22, 2018, which is a continuation-in-part of application No. 15/872,108, filed on Jan. 16, 2018, which is a continuation-in-part of application No. 15/203,882, filed on Jul. 7, 2016, now Pat. No. 10,703,483, which is a continuation-in-part of application No. 14/375,673, filed on Jul. 30, 2014, now Pat. No. 9,868,416, and a continuation-in-part of application No. 14/852,593, filed on Sep. 13, 2015, now Pat. No. 10,144,514, which is a continuation-in-part of application No. 13/138,183, filed as application No. PCT/US2010/000237 on Jul. 18, 2011, now Pat. No. 9,174,555, said application No. 16/884,479 is a continuation-in-part of application No. 16/430,061, filed on Jun. 3, 2019, which is a continuation-in-part of application No. 16/138,998, filed on Sep. 22, 2018, which is a continuation-in-part of application No. 15/878,488, filed on Jan. 24, 2018, now Pat. No. 10,780,857, which is a continuation-in-part of application No. 14/726,170, filed on May 29, 2015, now abandoned, which is a continuation-in-part of application No. 13/507,149, filed on Jun. 9, 2012, now Pat. No. 9,150,127, which is a continuation-in-part of application No. 11/639,088, filed on Dec. 14, 2006, now Pat. No. 8,251,444, said application No. 16/884,479 is a continuation-in-part of application No. 16/430,061, filed on Jun. 3, 2019, which is a continuation-in-part of application No. 16/138,998, filed on Sep. 22, 2018, which is a continuation-in-part of application No. 15/878,488, filed on Jan. 24, 2018, now Pat. No. 10,780,857, which is a continuation-in-part of application No. 14/600,932, filed on Jan. 20, 2015, now Pat. No. 9,902,298, which is a continuation-in-part of application No. 13/507,149, filed on Jun. 9, 2012, now Pat. No. 9,150,127, which is a continuation-in-part of application No. 11/639,088, filed as application No. PCT/US2010/000237 on Dec. 14, 2006, now Pat. No. 8,251,444, which is a continuation-in-part of application No. 11/639,088, filed on Dec. 14, 2006, now Pat. No. 8,251,444, said application No. 16/884,479 is a continuation-in-part of application No. 16/430,061, filed on Jun. 3, 2019, which is a continuation-in-part of application No. 15/878,488, filed on Jan. 24, 2018, now Pat. No. 10,780,857, said application No. 16/884,479 is a continuation-in-part of application No. 16/430,061, filed on Jun. 3, 2019, which is a continuation-in-part of application No. 15/872,108, filed on Jan. 16, 2018, said application No. 16/884,479 is a continuation-in-part of application No. 16/430,061, filed on Jun. 3, 2019, which is a continuation-in-part of application No. 15/203,882, filed on Jul. 7, 2016, now Pat. No. 10,703,483, said application No. 16/884,479 is a continuation-in-part of application No. 16/430,061, filed on Jun. 3, 2019, which is a continuation-in-part of application No. 15/143,168, filed on Apr. 29, 2016, now Pat. No. 10,556,523, said application No.

13/507,149 is a continuation-in-part of application No. 13/138,183, filed on Jul. 18, 2011, now Pat. No. 9,174,555.

- (60) Provisional application No. 63/028,004, filed on May 21, 2020, provisional application No. 62/971,946, filed on Feb. 8, 2020, provisional application No. 62/430,910, filed on Dec. 6, 2016, provisional application No. 62/480,071, filed on Mar. 31, 2017, provisional application No. 61/632,797, filed on Jan. 31, 2012, provisional application No. 61/685,537, filed on Mar. 20, 2012, provisional application No. 61/686,316, filed on Apr. 3, 2012, provisional application No. 61/688,591, filed on May 17, 2012, provisional application No. 61/688,855, filed on May 23, 2012, provisional application No. 61/744,431, filed on Sep. 26, 2012, provisional application No. 61/797,175, filed on Dec. 1, 2012, provisional application No. 61/797,639, filed on Dec. 12, 2012, provisional application No. 61/848,724, filed on Jan. 10, 2013, provisional application No. 61/402,751, filed on Sep. 3, 2010, provisional application No. 61/404,335, filed on Oct. 1, 2010, provisional application No. 61/458,997, filed on Dec. 3, 2010, provisional application No. 61/459,689, filed on Dec. 16, 2010, provisional application No. 61/460,266, filed on Dec. 29, 2010, provisional application No. 61/465,160, filed on Mar. 15, 2011, provisional application No. 61/062,002, filed on Jan. 23, 2008, provisional application No. 61/066,372, filed on Feb. 20, 2008, provisional application No. 61/072,241, filed on Mar. 28, 2008, provisional application No. 61/072,495, filed on Mar. 31, 2008, provisional application No. 61/123,345, filed on Apr. 8, 2008, provisional application No. 61/188,175, filed on Aug. 7, 2008, provisional application No. 61/191,309, filed on Sep. 8, 2008, provisional application No. 61/198,541, filed on Nov. 6, 2008, provisional

application No. 61/062,002, filed on Jan. 23, 2008, provisional application No. 61/066,372, filed on Feb. 20, 2008, provisional application No. 61/072,241, filed on Mar. 28, 2008, provisional application No. 61/072,495, filed on Mar. 31, 2008, provisional application No. 61/123,345, filed on Apr. 8, 2008, provisional application No. 61/188,175, filed on Aug. 7, 2008, provisional application No. 61/191,309, filed on Sep. 8, 2008, provisional application No. 61/198,541, filed on Nov. 6, 2008, provisional application No. 61/957,635, filed on Jul. 8, 2013, provisional application No. 61/959,598, filed on Aug. 28, 2013, provisional application No. 61/961,092, filed on Oct. 4, 2013, provisional application No. 61/961,367, filed on Oct. 12, 2013, provisional application No. 61/206,205, filed on Jan. 28, 2009, provisional application No. 61/208,445, filed on Feb. 24, 2009, provisional application No. 61/211,191, filed on Mar. 27, 2009, provisional application No. 61/214,672, filed on Apr. 27, 2009, provisional application No. 61/215,559, filed on May 7, 2009, provisional application No. 61/270,808, filed on Jul. 14, 2009, provisional application No. 61/276,298, filed on Sep. 9, 2009.
